UNITED STATES PATENT OFFICE

2,641,317

MACHINE FOR CUTTING STRIPS OF
TEXTILE FABRICS

Ingo Pasold, Toronto, Ontario, Canada

Application August 29, 1950, Serial No. 182,054
In Great Britain May 26, 1950

3 Claims. (Cl. 164—65)

1

This invention relates to machines for cutting strips from tubular textile fabrics.

Strips of textile fabric cut in such fashion that the two edges are relatively extensible are required in certain textile garment manufacturing processes, e. g. in the neck binding of knitted jumpers, sweaters, vests and the like.

A machine has been proposed for producing said strip from tubular fabric comprising one or more power-driven knives into contact with which the fabric is guided continuously by an operator so as to cut a finite length of tubular fabric in helical fashion into a continuous strip or strips.

Output from such a machine is necessarily limited by the skill and capability of the operator and in practice at least three strips are usually cut simultaneously in order that the output may be tolerably economic. If a length of helically cut strip knitted fabric is laid on a flat surface, it will be seen that the lateral rows of stitches do not lie truly at right angles to the edges of the strip, and if such strip is then curved while still remaining flat upon said surface, the lateral rows of stitches will be found to be decreasingly inclined to the edges of the strip from one end of the strip to the other, thus involving a lack of symmetry. Whilst this lack of symmetry is slight in the case of narrow strips, it becomes substantial in the case of wide strips, such, for example, as is involved when two or more strips are simultaneously cut, as in the machine referred to above.

The object of the present invention is to provide a machine which will automatically and economically cut strips of textile fabric from a tube thereof with a minimum of non-symmetry referred to above.

The invention consists in an automatic machine for cutting tubular textile fabric into a helical strip comprising means for supporting an end of the fabric tube, means for feeding the fabric tube axially in relation to said fabric supporting means, a power driven knife and a finger member, said knife and finger member being adapted partially to project into a circumferential groove or slot in said fabric supporting means, and power means for rotating said fabric supporting means relatively to said knife and finger.

The invention also consists in an automatic machine as set forth in the preceding paragraph, wherein said feeding means comprise a carding pad or pads on said fabric supporting means and a plurality of reciprocating arms carrying carding pads adapted to co-operate with said former pad or pads.

2

The invention also consists in an automatic machine as set forth in the preceding paragraph including also one or more rotary brushes adapted to engage the fabric in the vicinity of the said finger member.

The invention also consists in an automatic machine as set forth in any of the three preceding paragraphs wherein the fabric supporting means is stationary.

10 The invention also consists in an automatic machine as set forth in any of the four preceding paragraphs, wherein a drum is provided which is urged into contact with the cut strip or fabric and is adapted to receive and coil the cut strip thereon.

15 The invention also consists in an automatic machine as set forth in the preceding paragraph including mechanism adapted to stop the machine when the drum is loaded to a predetermined depth.

20 The invention also consists in machines for automatically cutting tubular textile fabric into a helical strip or strips substantially as herein-after described with reference to the accompanying drawings.

25 Referring to the accompanying diagrammatic drawings:

Figure 1 is a side elevational view of one convenient construction of machine embodying the present invention,

30 Figure 2 is a plan view thereof with parts broken away,

Figure 3 is a half vertical sectional view on the line III—III of Figure 2,

35 Figures 4 and 5 are enlarged sectional views of details.

40 In carrying the invention into effect according to one form illustrated by way of example in the accompanying drawings, a fixed vertical pillar *a* is provided carrying at its upper end a cylindrical head *b* furnished with a conical top *c*. Surrounding the pillar and adapted to rotate on ball bearings *d* thereon is a series of arms *e* upon which are mounted a plurality of vertical columns *f*, a ring *3*, a finger member *g*, an electric motor-driven rotary knife *h*, a rotary brush *i* and a spring-urged arm *j* for carrying a winding drum *k*.

45 The table structure comprising the arms *e*, pillars *f* and ring *3*, is adapted to be driven by gearing *m n* from a fixed motor *4*. A fixed bracket member *o* carries a ring *p* to which a plurality of arms *q* are pivoted at *r*, these arms rigidly carrying depending arms *s* and spring-urged pivoted arms *t*. The lower ends of the latter arms

carry at their lower ends carding pads *u* so disposed as to oscillate in vertical directions past a circumferential groove or slot *v* formed near the lower end of the conically topped head *c*.

A similar carded pad or strip *w* is provided on the conical topped head just above the aforesaid groove, the wires of the latter pads, however, being inclined oppositely to the wires of the pads on the oscillating arms, so that the textile material remains stationary as the oscillating pads move upwards but is moved downwards when the arms move downwards.

The lower ends of the arms *s* are engaged by a series of cams *x* supported on the rotary table *e*.

The brush *i* is adapted to be rotated by epicyclic gearing *z* from a fixed toothed ring *y* encircling the pillar *a*.

The cams *x* are furnished with screws 2 for adjustment whereby the stroke of the oscillating arms *t* may be varied to vary the amount of textile material that is fed downwards for each downward stroke of the arms; the width of the cut textile strip may thus be varied at will.

The cut material is laid around the spring-loaded drum *k* so that the strip as it is cut is wound on to the drum.

Convenient mechanism is provided to stop the machine when the drum has become loaded to a desired diameter.

In operation, one end of a tube of textile material is introduced over the conical end *c* of the head *b* and as the machine operates the lower edge of the tube is fed downwards by the moving carding pads *u* so that it passes over and beyond the groove or slot *v* in the head. Rotation of the finger *g* which projects partially into the aforesaid slot in conjunction with the rotary brush *i* assists the passage of the lower edge of the textile tube downwards over the slot. The rotating rotary knife *h* cuts the strip to the predetermined width and the strip is loaded on the drum *k*.

In the above construction of the machine, the

textile tube moves longitudinally as it is fed to the machine but does not rotate, but if desired the textile tube, feeding arms and feeding head may be caused to rotate whilst the knife or knives, finger, brush and cams for reciprocating the feeding arms, etc. may be stationary.

I claim:

1. In an automatic machine for cutting tubular textile fabric into a helical strip, cylindrical means for supporting an end of the fabric tube, means for feeding the fabric tube axially in relation to said fabric supporting means including a plurality of feeding fingers disposed in close juxtaposition around the periphery of said supporting means, a power driven knife and a guide finger member, said knife and guide finger member being adapted partially to project into a circumferential groove or slot in said fabric supporting means, and power means for rotating said fabric supporting means relatively to said knife and guide finger.

15 2. An automatic machine as claimed in claim 1, wherein said feeding fingers comprise reciprocating arms carrying carding pads adapted to co-operate with at least one carding pad on said fabric supporting means.

20 3. An automatic machine as claimed in claim 1, wherein the fabric supporting means is stationary.

30

INGO PASOLD.
